SEWING MACHINE

Otto Hess, Ludwigsburg, Wurtemberg, Germany

Application May 28, 1952, Serial No. 290,445

Claims priority, application Germany June 8, 1951

6 Claims. (Cl. 112—258)

The present invention concerns a sewing machine, particularly a high-speed sewing machine with pressure lubrication, in which are incorporated an oilpan below the sewing unit and an oil pump sucking off the oil out of the oilpan and feeding it to the lubricating points of the sewing unit.

It is the object of the present invention to locate the sewing unit on the oilpan, as well as to mount the oilpan in the table of the sewing machine in such a manner as to prevent the vibrations of the sewing unit during operation from being transmitted to the oilpan and the oil contained therein, and to prevent the oil from penetrating directly from the oilpan to the stitching parts of the sewing unit or to the workpiece.

Another object of the invention is to seal the oilpan in such a manner as to prevent the downy fibers of the worked material and the dust from penetrating into the interior of the machine, which may be the cause of breakdown.

In view of this I provide in a high-speed sewing machine a sewing unit including a ground-plate supporting the sewing unit, a table with a substantially rectangular cut-out portion, an oilpan, located below the sewing-unit and suspended in said cut-out portion and provided with parts adapted to support said oilpan in said cut-out portion, cushions made of resilient materials arranged between said table and said supporting parts of the oilpan, the bottom of said sewing-unit including the ground-plate being arranged at the top edge of said oilpan, an intermediate layer made out of resilient, oil-resistant material inserted between said bottom of said sewing-unit and said top edge of said oilpan, at least one screw penetrating said ground plate and connecting together said ground plate and the bottom of said oilpan, resilient oil-resistant material, arranged between said screw and said ground plate, an oil pump adapted to feed oil from said oilpan to said sewing unit.

Other objects and advantages of the present invention will be pointed out in the hereinafter following description of an illustrative embodiment thereof, or will be understood by those conversant with the subject. In the accompanying drawing is:

Fig. 1 a view of the sewing machine with a longitudinal sectional view of the oilpan;

Fig. 2 a top view of the oilpan;

Fig. 3 a top view of the oilpan;

Fig. 4 a fragmentary sectional view of one end of the oilpan showing the mounting of the sewing unit on the oilpan;

Fig. 5 an enlarged sectional view of another realization of the mounting of the sewing unit on the oilpan, and

Fig. 6 a sectional view of a further execution of the connection between the ground plate and the oilpan.

The sewing machine according to the invention comprises a table 8, which is supplied with a substantially rectangular cut-out portion 7. In this cut-out portion 7 an oilpan 2 is suspended by means of support arms 9

2

located at the top edge 2' of the oilpan 2, preferably at the four angles thereof.

The edge of the cut-out portion 7 of the table 8 is formed with recesses 23, in which the support arms 9 are inserted. The support arms 9 do not rest directly against the ground surface of the recesses 23, but a cushion 10 made of resilient material, e. g. rubber, is interposed between each support arm 9 and the corresponding recess 23. Each of the cushions 10 is suitably connected with the corresponding support arm 9 intermediate a screw 24, which preferably is arranged countersunk in the cushion 10. Besides this the ground surface of each recess 23 is formed with a cavity 23' into which the cushion 10 is inserted.

15 It is suitable to reinforce the top edge 2' of the oilpan 2, compared with the other sides of the oilpan. This reinforced edge 2' carries the sewing unit 1 mounted on the ground-plate 22.

The sewing unit 1 may be designed in any suitable manner. It comprises all parts necessary to perform the sewing functions according to conventional practice.

25 As the oilpan 2 has four sides, the top edge 2' of the oilpan is composed of four parts positioned in one plane. The top edge 2' of the oilpan 2 at the inner portions of the four parts are formed with an open groove running all-around the top edge 2'. A resilient, oil-resistant intermediate layer 12 made out of rubber, e. g., is inserted into the groove 11. The intermediate layer 12 is projecting beyond the upper surface of the parts forming the top edge 2' of the oilpan 2. Upon the intermediate layer 12 rests the sewing unit 1 by means of the ground plate 22, to which end the sewing unit 1 is surrounded by a flange 1'.

35 As set forth in Fig. 5 substantially, it is suitable that the supporting face of the sewing unit 1, i. e., the bottom face of the flange 1', which rests upon the resilient oil-resistant intermediate layer 12, is supplied with flutes 25 arranged in parallel direction to the sides of the oilpan 2. The flutes 25 form between them a rib 26 having 40 the shape of an edge. As the bottom face of the flange 1' compresses the resilient intermediate layer 12, the edge 26 penetrates into the said layer 12, thus achieving a reliable sealing of the oilpan. The sewing unit 1 and the oilpan 2 are connected to each other by at least one, 45 preferably two screws 16.

According to the realization set forth in Fig. 1, the ground-plate 22 has a bore 27. The screw 16 penetrates through the bore 27 without touching the walls thereof. The bore 27 is covered by a perforated cylinder 28 made out of resilient and oil-resistant material, for example rubber. The screw 16 penetrates the perforation of the cylinder 28 which is compressed by the head 29 of the screw 28. The screw 28 is screwed into the bottom 2" of the oilpan 2, so that an oil-tight connection is produced 55 between the sewing unit 1 and the oilpan 2, which connection, however, does not transmit any vibrations.

The ground plate 22 of the sewing unit 1 as well as the bottom 2" of the oilpan 2 are appropriately reinforced by eyes 30, located within the range of the screw connection.

60 A second realization according to Fig. 6 is characterized by a ground plate 22, a bore 14 and a concentric recess 31. The bore 14 and the recess 31 are filled up by a flanged bushing 15 made of resilient, oil-resistant material, e. g. rubber. The screw 16' penetrates a bore of the bushing 15 and is screwed in the bottom 2" of the oilpan 2. A resilient compression spring 17 is arranged between the head 29' of the screw 16' and the top surface of the flange of the bushing 15.

An oil pump 3 is mounted in an opening of the ground plate 22, which opening may be shaped as a collar 32. The oil pump 3 feeds oil to the lubricating points of the

sewing unit 1, the oil thereat circulating in a closed cycle.

Opposite to the oil pump 3, the bottom 2" of the oilpan 2 has a spherical thickening 21 which flattens down radially from the centre axis of the oil pump 3. This thickening causes impurities to glide down at this point; so that they do not reach into the pump 3.

The bottom 2" of the oilpan 2 descends in the direction from the wall of the oilpan 2 adjacent to the thickening 21 to the opposite wall of the oilpan 2. An oil outlet 33 capable to be closed by a drain plug 18 is located at the deepest level of the oilpan 2. Furthermore, the bottom 2" of the oilpan 2 is provided with leading ribs 19, located obliquely to each other and destined to lead the oil in the neighbourhood of the oil outlet 33, thus preventing the re-entrance of impurities into the lubricating oil.

Also the ground-plate 22 of the sewing unit 1 is inclined with respect to the horizontal plane. An opening 34 is supplied at the deepest point of the ground plate 22. In the opening 34 an oil filter 35 is inserted, which allows the oil dropping down from the sewing unit 1 to the ground-plate 22 to return into the oilpan 2.

The driving motor 4 is mounted below the oilpan 2. It drives the sewing machine through pulleys 36 and 37 by means of a belt which is not represented in the drawing. The oil pump 3 is operated in any suitable manner by the sewing unit 1.

The driving motor 4 is adapted to suck-in cooling air at one side and to blow it off at the opposite side, as represented by the arrows A, B, C in the drawing. This cooling-air strikes the lower surface of the oilpan 2, which, in the region submitted to the cooling effect, is supplied with webs 38, so that the oil contained in the oilpan 2 is cooled.

What I claim is:

1. In a high-speed sewing machine having a table with a cut-out portion and a sewing unit with a bed provided with depending side and end walls and an oilpan secured to said bed and arranged within the cut-out portion of said table and supported by said table and having upturned walls forming a chamber with said bed, a frame structure comprising means for connecting the bed and oilpan together and with said table, said bed being rectangular and provided with a bottom plate integral with the bed to form a separate chamber adapted to receive driving mechanism of the sewing unit, said bed on its side and end walls being provided with a circumferential flange arranged in a horizontal plane in a lower part of the walls above the bottom plate, the oilpan having upturned walls ending in a horizontal reinforced top edge, the inner portion of which are provided with a circumferential open groove, the lower part of the bed below the flange being shaped to enter the oilpan and thereby the oilpan supports the bed and the sewing unit, a resilient oil-resisting intermediate layer between said flange and said groove, means for tightly connecting said bed and said oilpan together, the cut-out portion in the table receiving the upper part of the oilpan with a distance spaced between the walls and the reinforced top edge of the oilpan and the edges of the cut-out portion, support arms at each corner of the top-edge of the oilpan, the table being provided with recesses at the edges of the cut-out portion corresponding to the support arms, a cushion of resilient material arranged in each recess at the edges, and an oil pump being provided in a bore of a boss of the bottom plate of the bed, and the bottom of said oilpan being provided with a projection of substantially spherical form coaxially with the oil pump to permit impurities contained in the oil to slide down on the spherical form and escape to the pump.

2. In a high-speed sewing machine having a table with a cut-out portion and a sewing unit with a bed provided with depending side and end walls and an oilpan secured to said bed and arranged within the cut-out portion of said table and supported by said table and having up-

turned walls forming a chamber with said bed, a frame structure comprising means for connecting the bed and oilpan together and with said table, said bed being rectangular and provided with a bottom plate integral with the bed to form a separate chamber adapted to receive driving mechanism of the sewing unit, said bed on its side and end walls being provided with a circumferential flange arranged in a horizontal plane in a lower part of the walls above the bottom plate, the oilpan having upturned walls ending in a horizontal reinforced top edge, the inner portions of which are provided with a circumferential open groove, the lower part of the bed below the flange being shaped to enter the oilpan and thereby the oilpan supports the bed and the sewing unit, a resilient oil-resisting intermediate layer between said flange and said groove, means for tightly connecting said bed and said oilpan together, the cut-out portion in the table receiving the upper part of the oilpan with a distance spaced between the walls and the reinforced top edge of the oilpan and the edges of the cut-out portion, support arms at each corner of the top-edge of the oilpan, the table being provided with recesses at the edges of the cut-out portion corresponding to the support arms, a cushion of resilient material arranged in each recess at the edges, and the bottom of the oilpan being arranged inclined with respect to the horizontal, a projection provided in the higher part of said bottom, and an oil outlet provided at the deepest point of said bottom, ribs being provided on said bottom and arranged in a direction to feed the oil to said outlet.

3. In a high-speed sewing machine having a table with a cut-out portion and a sewing unit with a bed provided with depending side and end walls and an oilpan secured to said bed and arranged within the cut-out portion of said table and supported by said table and having upturned walls forming a chamber with said bed, a frame structure comprising means for connecting the bed and oilpan together and with said table, said bed being rectangular and provided with a bottom plate integral with the bed to form a separate chamber adapted to receive driving mechanism of the sewing unit, said bed on its side and end walls being provided with a circumferential flange arranged in a horizontal plane in a lower part of the walls above the bottom plate, the oilpan having upturned walls ending in a horizontal reinforced top edge, the inner portions of which are provided with a circumferential open groove, the lower part of the bed below the flange being shaped to enter the oilpan and thereby the oilpan supports the bed and the sewing unit, a resilient oil-resisting intermediate layer between said flange and said groove, means for tightly connecting said bed and said oilpan together, the cut-out portion in the table receiving the upper part of the oilpan with a distance spaced between the walls and the reinforced top edge of the oilpan and the edges of the cut-out portion, support arms at each corner of the top-edge of the oilpan, the table being provided with recesses at the edges of the cut-out portion corresponding to the support arms, a cushion of resilient material arranged in each recess at the edges, and the bottom of the oilpan being arranged inclined with respect to the horizontal, a projection provided in the higher part of said bottom, and an oil outlet provided at the deepest point of said bottom, ribs being provided on said bottom and arranged in a direction to feed the oil to said outlet.

4. In a high-speed sewing machine having a table with a cut-out portion and a sewing unit with a bed provided with depending side and end walls and an oilpan secured to said bed and arranged within the cut-out portion of said table and supported by said table and having upturned walls forming a chamber with said bed, a frame structure comprising means for connecting the bed and oilpan together and with said table, said bed being rectangular and provided with a bottom plate integral with the bed to form a separate chamber adapted to receive driving mechanism of the sewing unit, said bed on its

side and end walls being provided with a circumferential flange arranged in horizontal plane in a lower part of the walls above the bottom plate, the oilpan having upturned walls ending in a horizontal reinforced top edge, the inner portions of which are provided with a circumferential open groove, the lower part of the bed below the flange being shaped to enter the oilpan and thereby the oilpan supports the bed and the sewing unit, a resilient oil-resisting intermediate layer between said flange and said groove, means for tightly connecting said bed and said oilpan together, the cut-out portion in the table receiving the upper part of the oilpan with a distance spaced between the walls and the reinforced top edge of the oilpan and the edges of the cut-out portion, support arms at each corner of the top-edge of the oilpan, the table being provided with recesses at the edges of the cut-out portion corresponding to the support arms, a cushion of resilient material arranged in each recess at the edges, and the bottom plate of said bed being arranged inclined with respect to the horizontal, the deepest point of said bottom plate being provided with an opening, and an oilfilter provided arranged to drop the filtered oil into the oilpan.

5. In a high speed sewing machine having a base plate forming part of the bottom frame of the machine and provided with a flange, an oil pan comprising a bottom member and side walls with top edges to cooperate with the flange of the bottom frame, means connected to the bottom member and the base plate to secure the oil pan to the bottom frame with a tight connection of the top edges with the flange of the bottom frame, the bottom member with the side walls and the base plate forming a separate chamber for the oil, supporting arms secured to the top edges of the oil pan in spaced relationship acting to support the sewing machine, a projecting portion provided on the bottom member extending a short

35

distance above the inner surface of the bottom member, and a pump mounted in the base plate and extending just above the projecting portion, the latter preventing impurities from entering the pump.

5. In a high speed sewing machine having a base plate forming part of the bottom frame of the machine and provided with a flange, an oil pan comprising a bottom member and side walls with top edges to cooperate with the flange of the bottom frame, means connected to the bottom member and the base plate to secure the oil pan to the bottom frame with a tight connection of the top edges with the flange of the bottom frame, the bottom member with the side walls and the base plate forming a separate chamber for the oil, supporting arms secured to the top edges of the oil pan in spaced relationship acting to support the sewing machine, and the outer surface of the bottom member being provided with a plurality of fins acting to cool the oil in the pan by air streaming past the fins from a fan on a driving motor of the sewing machine secured to the bottom member of the oil pan.
